W. DAMM

ADJUSTABLE CURTAIN SUPPORT

Filed Aug. 7, 1926

Fig. 1.

Fig. 2.

UNITED STATES PATENT OFFICE.

WALTER DAMM, OF PATERSON, NEW JERSEY, ASSIGNOR OF ONE-HALF TO JOEL E. CRANDALL, OF PATERSON, NEW JERSEY.

ADJUSTABLE CURTAIN SUPPORT.

Application filed August 7, 1926. Serial No. 127,735.

The object of this invention is to provide a structure for supporting the means by which curtains, draperies and the like (hereinafter termed curtains) are hung at window or other openings which may be secured in place without the use of nails, screws or other devices to mar the woodwork at such an opening and which will be adjustable to fit openings of different width, and which will further be made so as when packed for shipment or when not in use to require the minimum of space.

In the drawing,

Fig. 1 is an inside elevation of a window opening having my curtain supporting structure secured in position;

Fig. 2 is a plan, the frame of the window opening being shown in horizontal section on line 2—2, Fig. 1;

Fig. 3 is an enlarged fragmentary horizontal section on line 3—3, Fig. 1;

Figs. 4 and 5 are front and side elevations of one of the main brackets; and

Fig. 6 is a front fragmentary elevation of the telescopic rod; and

Fig. 7 shows in perspective a detail thereof.

Let 1 designate the stiles of a window opening. In place of using brackets which have to be secured to the stiles by screws, nails or the like I utilize brackets which are held against the stiles, at their inside or opposed surfaces 1^a, by means acting to press them apart. These brackets, designated 2, not only bear against said surfaces but also against the inner surfaces 1^b of the stiles, which construction serves to guide and steady them in securing the brackets in place and also adapts the brackets for the proper positioning thereon of the means by which the curtain or curtains is or are supported. Each bracket consists of a plate bent at right angles to form two wings 2^a, 2^b, respectively adapted to bear against the surfaces 1^a, 1^b of the window stile. The wings 2^a of the two brackets have opposed arcuate slots 3, the purpose of which will later appear.

Between the brackets is a telescopic rod including telescoping sections 4 and 5. Each rod section has its outer end formed to provide a separable connection with the corresponding bracket 2, in the present case a connection of the bayonet-joint type. For this purpose such end of the rod section preferably has diametrically opposite L-shaped notches 6 formed therein, thus pro-

viding diametrically opposite hooks (Fig. 7) to enter the slots 3 in the plate and on turning the rod section in the appropriate direction on its own axis to engage with the bracket. Upon being thus connected with the brackets 60 the rod is extended and held as extended as follows:

On the outer rod section 4 is secured a fitting 6. In the present example this comprises two spaced annular portions 6^a, 6^b surrounding and fitting said rod section and joined by the integral web 6^c which has a longitudinal slot 6^d. The two portions 6^a and 6^b might be independently brazed or otherwise secured on the rod section, but I preferably form them 65 integral, with the connecting web, so as to fasten the fitting in the following secure manner on the rod section: Before the fitting is slipped over the rod section the inner (or what I term the telescoping) end of the latter 70 is flared to form a stop or shoulder 4^a, and a locking tongue 4^b is formed thereon, by suitably cutting the metal, in spaced relation to the stop or shoulder and so as to project toward the same; thereupon the fitting is 75 slipped over the rod section from its opposite end and forced past the tongue which, when cleared, springs back outward and holds the fitting portion 6^a locked between itself and the shoulder 4^a. The fitting portion 6^b has 80 a bifurcated extension in which is pivoted a lever 7 movable in a plane coincident with the axis of the rod. This lever has pivoted to it at its inner side, so as to move in the same plane and in the slot 6^d, a pawl 8. The pawl is adapted to engage suitably spaced notches 9 arranged to extend in a series longitudinally of and in the rod section 5, said notches being here afforded by holes in said rod section.

The rod sections being telescoped and the brackets fitted to their outer ends as described the support thus afforded is placed between the stiles 1 in horizontal position and then it is extended until the brackets bear against the opposed faces of the stiles, the brackets being also kept bearing against the inner faces of said stiles. The pawl 8 is then engaged in one of the appropriate notches 9, whereupon the lever 7 is shifted inward so that it and the pawl coact to force the rod sections apart and so establish the necessary permanent pressure of said support against the stiles. How the lever is locked in its inward position is not material; but I show a ring keeper 10 pivoted 95

in the fitting portion 6^a to engage over its free end.

As indicated, the present invention is not broadly concerned with the type of curtain to be supported. I show the brackets, however, equipped for the support of curtains of the drapery class. To this end, by slitting the metal of each bracket wing 2^b on spaced parallel horizontal lines and then bending outward the intervening metal supporting loops 11 are formed and these are adapted to receive hangers 12 consisting of short lengths of metal stock bent at right angles in planes perpendicular to each other so that one extremity 15 may be entered into a loop 11 (or a pair of them Fig. 4) and the other may enter and thus support one end of the tubular rod 13 on which the drapery directly hangs. To protect the woodwork against scratching by the brackets 2 and from being marred by the pressure which is exerted thereon by the telescopic rod a pad 14 of felt or other suitable soft material is interposed between each bracket and the window stile. To impart a finish to each 20 bracket and hide the cushion afforded by its pad 14, the edges of the bracket are turned in as shown in Fig. 3 at 2^c.

Having thus fully described my invention what I claim and desire to secure by Letters 30 Patent is:

1. In a curtain-supporting means, a telescopic support adapted on telescopic adjustment thereof to bear against oppositely facing surfaces and thus be supported and including 35 a pair of telescopically movable members, a

lever pivoted to one member to move in a plane extending lengthwise of the line in which said members are telescopically movable, and a pawl pivoted to the lever to move also in a plane extending lengthwise of said 40 line and engageable with the other member to lock said members against telescopic collapse.

2. In a curtain-supporting means, a telescopic support adapted on telescopic adjustment 45 thereof to bear against oppositely facing surfaces and thus be supported and including a pair of telescopically movable members, the outer one of which has an external stop at its end and, removed from such end, a locking 50 tongue, a fitting slipped over the relatively outer member from its other end and held between said stop and tongue and means, movable in said fittings to releasably secure said members against telescopic collapse. 55

3. In a curtain-supporting means, the combination of a plate to bear against one of two opposite spaced surfaces of a window frame, and a tubular rod member, the plate having an arcuate slot and the free end of said member being adapted to bear against the plate and having hooks at said end thereof and formed in its tubular wall and enterable into said slots and adapted to interlock with the plate on turning said member on its own axis, 60 whereby the plate will then form a pressure terminal on said member adapted to bear against one of said surfaces. 65

In testimony whereof I affix my signature.

WALTER DAMM.
